UNITED STATES PATENT OFFICE

1,967,644

PRIMER VALVE

David S. Williams, Portland, Oreg.

Original application December 30, 1933, Serial No. 704,637. Divided and this application March 6, 1934, Serial No. 714,210

9 Claims. (Cl. 182—12)

This invention relates in general to improvements in valves, and particularly to primer valves which are adapted for automatic actuation by water pressure that normally is contained in a water supply line but which utilizes somewhat different mechanical principles from those set forth in my co-pending application for improvements in "Primer valves", Serial No. 704,637, filed December 30, 1933, out of which this application has been divided to comply with rule 10 of the rules of practice in the United States Patent Office, and from those set forth in my co-pending divisional application for the improvements in "Primer valves", Serial No. 714,805, filed March 9, 1934.

The subject matter of this application is capable of fulfilling all of the objects set forth in the above-identified co-pending applications, insofar as the subject matter common to the three is concerned, and, while the device illustrated as embodying the present invention is particularly designed for use with water traps of the well-known type, still it may have a wide and varied range of utility in other arts where it is essential to automatically actuate a valve by water pressure.

My invention contemplates the provision of a primer valve which may be automatically actuated so that a water seal is at all times maintained in floor drain traps, sumps or other analogous contrivances so that the obnoxious gases usually generated in sewers and other disposal units cannot enter into houses or buildings from such sewers or other disposal units.

An important object of my invention is to provide a valve which, when installed directly or indirectly in a water supply line running to or from any service connection, will automatically maintain a predetermined amount of water as a seal against escaping obnoxious gases and/or will compensate for water losses in devices connected thereto due to use, evaporation, leakage or other causes.

An equally important object of my invention is to provide means for preventing foul water and air to be siphoned from any drains into the water supply line.

A still further object of my invention is to provide a simple, practical, inexpensive and efficient primer valve which may be manufactured at low cost and within a minimum of time.

The invention is directed to other objects and possesses other features of novelty and advantage and consists in the new and useful formation, construction, combination and interrelation of parts, members and features, all of which will be more apparent from the following detailed description, having reference to the accompanying drawing which illustrates two embodiments

by which the invention may be realized and in which:

Figure 1 is a sectional, side view of a priming unit embodying my invention, showing the position of the valve when the liquid in the supply line is at rest.

Figure 2 is a sectional, side view of a priming unit embodying my invention, showing the position of the valve when the liquid in the supply line is in motion.

Figure 3 is a fragmentary, side view, partially in section, of the priming unit illustrated in Figures 1 and 2, showing, in addition, a resilient member positioned in such manner as to normally maintain the movable portion of the valve in the position shown in Figure 1.

Figure 4 is a sectional, side view of a priming unit embodying a slightly modified form of my invention, showing the position of the valve when the liquid in the supply line is at rest and further showing a slightly modified form of vent arrangement.

Figure 5 illustrates a water supply line to which a standard type of faucet is attached and also to which a priming unit embodying my invention is directly connected and further indicating the manner of connecting said unit to a water trap.

Corresponding and like parts are referred to in the following description and indicated in all of the views of the drawing by the same reference characters.

The preferred form of my invention is completely illustrated in Figures 1 and 2, wherein reference character A designates generally the priming unit. The valve-body or casing 1 has an internal threaded boss 2 and an external threaded boss 3 extending in the opposite direction from boss 1 but in direct alignment therewith. A dividing wall or diaphragm 4 separates the passageway formed between two bosses into chambers 5 and 6. The dividing wall or diaphragm 4 has an opening 7 disposed therethrough, whose circumference is materially less than the circumference of the inner wall of the passageway. A port 8 is disposed through the lower portion of the diaphragm 4, and assists in more effectively equalizing the pressure throughout the interior of the valve-body when the water supply is cut off.

Internal threaded boss 9 extends upwardly from the valve-body 1 and head-cap 10 is threadably secured thereto. The head-cap is formed with a chamber 11 therein into which enters a portion of the valve-stem 32, hereinafter to be more particularly described. A guide-flange 12 is formed about the periphery of the chamber 11 and acts as a guide for the valve-stem 32. If it is desired to supply a resisting force against the upper portion of the valve-stem 32 to be described, a resilient member 13, such as a rubber diaphragm, may be placed within the chamber 120

11, as graphically indicated in Figure 3, wherein there is shown the base 14 of the resilient member resting against the ceiling 15 of the head-cap 10 and the apex 16 of the diaphragm 13 resting 5 against the top of the valve-stem 32.

External threaded boss 17 extends downwardly from the valve-body 1 and is in direct alignment with the internal threaded boss 9. A flange-guide 18 extends upwardly from boss 17 into 10 chamber 5. A hollow-stem or supply-tube 19 is removably disposed within the boss 17 so that the apex 20 of the supply-tube 19 is positioned below the flange-guide 18. The supply-tube 19 has a flange 21, which rests against the face 22 of the 15 boss 17. A restricted opening 23 is formed through the apex 20 of the supply-tube 19.

A vent-assembly 24 has a bore 25 therethrough. One end of the vent-assembly 24 has a flange 26 adjacent its periphery, and the other end has an 20 internal threaded boss 27 formed therein. The vent-assembly 24 is connected to the valve-body 1 by placing the flange 26 against the flange 21 so that the bore 25 of the vent-assembly is in registerable alignment with the interior 28 of the 25 supply-tube. Both of these flanges are held in connected relationship by union-coupling 29, which is threadably disposed on boss 17. A plurality of vent-openings 30 extend through boss 27, and a canopy or vent-protector 31 is slidably disposed about the vent-assembly 24 and normally 30 covers the vent-openings 30. Attention might well be called to the fact that the vent assembly fulfills several important functions. Not only does the vent assembly permit inspection and 35 supply air to the supply tube, but it also eliminates the possibility of a siphon action taking place between the supply tube and the drain to which the vent assembly is connected. Thus the possibility of foul water and air in the drains being 40 siphoned into the water supply line and contaminating the water therein is entirely prevented.

The movable member of the priming unit consists of a valve-stem 32 that has a resilient element 33, such as a valve-washer, removably secured to one of its ends. This end normally rests against opening 23 in the supply-tube 19 so that the washer effectively seals the opening in order to prevent any liquid entering into the interior 28 of the supply-tube when the liquid in the supply 45 line is at rest. The valve-stem passes through the opening 7 in the diaphragm 4 and is held in relatively vertical position by guide-flanges 12 and 18. A weighted flange 34, whose outer circumference is substantially equal to the circumference of the 50 opening 7, is secured to the valve-stem 32 and is positioned thereon, so that when the end of the valve-stem 32, which has valve-washer 33 therein, is at rest upon the apex 20 of the supply-tube, thus sealing opening 23, the base 35 of the 55 weighted flange is placed immediately adjacent the upper portion of the diaphragm 4. By this arrangement the full weight of the valve-stem assembly is applied upon the apex 20 to seal effectively opening 23, and, at the same time, for 60 all practical purposes, to seal opening 7. A supply-port 36, the function of which is to keep a ready supply of water around the apex 20 of the supply-tube 19 ready to enter within the interior 65 thereof when the valve-stem assembly is raised and the restricted opening 23 unsealed, is disposed through the guide-flange 18.

A slightly modified form of the invention heretofore described is illustrated in Figure 4, wherein there is shown the general outline of the valve-body 1 shown in Figures 1 and 2, but whose in-

terior is slightly modified. The chamber 11 of the head-cap 10 is smaller in area, thus eliminating the necessity of flange 12 shown in Figures 1, 2 and 3. The diaphragm 4 illustrated in Figures 1 and 2 is modified so that there is provided a 80 practically unrestricted passageway between bosses 2 and 3, thus providing a straight-way valve through which the liquid in a supply line may pass with greater freedom of movement, since the port 8 is materially increased in area as 85 shown at 37 so that a greater proportion of water can pass directly from chamber 5 into chamber 6 instead of requiring a greater proportion of the liquid to pass through opening 7 into chamber 6 as required in the construction illustrated in Figures 1 and 2. Guide-flange 18 is also slightly modified by reducing its over-all area and by adding thereto an additional supply-port 38. The valve-stem 32 is substantially identical in construction as that illustrated in Figures 1 and 2 90 with the exception that the circumferential area of the lower portion is materially reduced, thereby permitting the weight of the flange 39 to be materially reduced, but its circumferential area is still substantially identical to the circumference of 95 the opening 7. It is obvious that the resilient member 13, illustrated in Figure 3, may also be applied to this modified form of the invention to perform the identical functions for which it is intended.

The vent-assembly 24 has also been slightly modified but performs the identical functions as the vent-assembly heretofore described. The modified form consists of an internal threaded member 40, which has a plurality of threaded 100 arms 41 extending from the top 42 of the member 40 and inclining inwardly. These arms are threadably positioned upon the hollow-stem 43 of the vent-assembly 24, and, by this construction, vent-openings similar to those illustrated 105 in Figures 1 and 2 are automatically provided. A slightly modified form of protector or vent-cover 44 is slidably positioned with respect to the stem 43.

There is illustrated in Figure 5 one of the valves 110 directly connected with a supply line. Boss 2 has threaded conduit 45, coming from a source of water supply not shown, and conduit 46 is joined to boss 3 by union-coupling 47. Conduit 46 is shown connected to a standard faucet 48, 115 but it is obvious that conduit 46 may be connected to any other service outlet without affecting the operation of the invention. Boss 27, through proper conduit connections, may be joined with a drain trap 49 or with any other contrivances 120 which require an intermittent supply of water either for purposes of effecting a seal or for any other purpose. The application of this invention to a drain trap should not be considered a limitation to its use since the invention has a wide 125 range of utility and may be applied to other arts and for other purposes.

Modus operandi

It is well known that water systems are constructed so that sufficient pressure is maintained in all supply lines either by natural or artificial means. It is the purpose of the invention to utilize the pressure maintained within water supply lines for permitting the automatic actuation of 140 a valve in order to permit some of the water within the supply line to be diverted and bypassed for the purpose of producing a water seal or for any purpose where it is desired to maintain automatically a substantially constant sup- 145-150

ply of water. When a service outlet is opened, the water within the supply line is put into motion and surges forward toward the valve assembly. As the water rushes into chamber 5, its flow is 5 suddenly diverted by diaphragm 4, causing a turbulence of sufficient force to raise the valve-stem assembly as the water seeks to enter chamber 6 through opening 7. When the valve-stem assembly is raised, opening 23 is uncovered and water 10 is permitted to enter into the interior 28 of the supply-tube 19, as shown in Figure 2, and from there the water enters into the water-trap or any other contrivance to which the vent-assembly is connected. When the service outlet is closed, 15 the surge of the water is reduced and the water in the supply line is put to rest and consequently the weight of the valve assembly is sufficient to cause the valve-stem to reach its dormant position and to seal effectively opening 23, as shown 20 in Figure 1.

The invention has been described in connection with two specific, illustrative embodiments disclosing a definite arrangement of parts. However, it will be understood that a wide range of 25 variants thereof are possible to those skilled in the art without departing from the broad spirit of this invention, since the invention, in its broader aspect, is not limited to the specific construction herein described and shown, as changes 30 in the size, proportions, arrangements and mechanical relations as well as additions, omissions and substitutions in the form or part may be made which fall within the scope of the subject matter incorporated in the appended claims.

35 Having thus described my invention, what I claim as new and upon which I desire to secure Letters Patent is:

1. In a device of the class described, in combination, a body member having an inlet passageway and an outlet passageway, a wall disposed in spaced relationship between said passageways, means, disposed within the body member and passing through the wall, responsive to the pressure of the water passing through the 40 body member, and a hollow stem removably disposed within the body member in direct alignment with said means, said hollow stem having an opening therein adapted to be sealed by said means when said means is in normal dormant position.

2. In a device of the class described, in combination, a body member having an inlet passageway and an outlet passageway, a diaphragm disposed between and dividing said passageways, means disposed within and vertically movable with respect to the body member and passing through the diaphragm responsive to the pressure of water passing through the body member, a hollow-stem removably disposed within the 45 body member in direct alignment with said means, said hollow-stem having an opening therein adapted to be sealed by said means when said means is in normal dormant position, and a vent-assembly removably secured to the hollow-stem.

3. A device characterized as in claim 2, wherein the vent-assembly consists of a conduit in registerable alignment with said hollow-stem, vent-openings disposed through said conduit, and a vent-protector surrounding said conduit and normally covering said openings.

4. A device characterized as in claim 2, wherein the means therein-mentioned consists of a valve-stem, a weighted flange the circumference of which is substantially equal to the circumference of the opening within the diaphragm being disposed upon said valve-stem in such position as to normally maintain said opening in a substantially covered condition, and a resilient element removably disposed within the base of said valve-stem, said resilient element normally sealing the opening in said hollow-stem.

5. A priming unit of the class described comprising, a body-member having a plurality of bores therethrough, a diaphragm dividing all of said bores into chambers, said diaphragm having an opening therein and a port therethrough, a supply tube removably disposed within one of said bores, said supply tube having a restricted opening at one end thereof, and a valve-member disposed within the body-member and vertically movable therein, said valve-member adapted to normally cover the restricted opening in the supply tube and the opening in the diaphragm and to respond to the pressure of the water passing through the body-member to uncover said 100 openings.

6. A device characterized as in claim 5, including a vent-assembly in registerable alignment with the supply tube.

7. In combination with a source of water supply under pressure, a primer-valve having a body-member which has two passageways at right angles to each other passing therethrough, a diaphragm disposed in such manner within the body-member as to divide said passageways into 105 chambers, said diaphragm having an opening therein, a supply tube removably disposed within the lower portion of one of said passageways, said supply tube having a valve-seat formed at one end thereof with an opening therethrough, 110 and means positioned upon said valve-seat for normally maintaining the interior of said supply tube out of communication with said chambers and for normally maintaining the opening within the diaphragm in a relatively covered condition, said means adapted for vertical movement 115 and responsive to water pressure applied thereunder.

8. A primer valve, comprising a body-member having an inlet passageway and an outlet passageway, a diaphragm dividing the body member into a plurality of chambers and having an opening therein disposed between said chambers, a hollow-stem, having an opening therein removably disposed within the body-member, a valve-stem vertically movable within the body-member and being in registerable alignment with the valve-stem opening, and a flange disposed about the valve-stem, said valve-stem assembly adapted for being moved vertically by water under 120 pressure.

9. A device characterized as in claim 8, including means for guiding said valve-stem in its vertical movement with respect to the body-member, a vent-assembly removably secured to the hollow-stem and in communication therewith, comprising a conduit, a vent-creating member threadably disposed thereon, and a covering slidably disposed with respect to the conduit and normally covering the vent member.

DAVID S. WILLIAMS. 145
